(57) **CLAIM**

The ornamental design for an outdoor cart frame as shown and described.

DESCRIPTION

FIG. 1 is a perspective view of an outdoor cart frame showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 1; and, FIG. 10 is an enlarged view of portion 10 shown in FIG. 2. The broken lines in the drawings depict portions of the outdoor cart frame that form no part of the claimed design. The dot-dash broken lines in FIGS. 1-2 and 9-10 represent boundaries of the enlarged portions and form no part of the claimed design.
